MANUFACTURE OF STAPLE FIBER MATERIALS FROM CONTINUOUS FILAMENTS

Henry Dreyfus, London, and William Pool, Spondon, near Derby, England, assignors to Celanese Corporation of America, a corporation of Delaware

Application July 27, 1937, Serial No. 155,948
In Great Britain July 31, 1936

17 Claims. (Cl. 57—157)

This invention relates to the manufacture of staple fiber materials from continuous filaments, and has for its object to produce continuous staple fiber products containing cut staple fibers of predetermined length directly from continuous filaments, e. g., cellulose acetate, viscose, cuprammonium, or natural silk filaments, or mixtures of two or more of these.

According to the invention a substantially twistless bundle of associated continuous filaments is continuously converted into a sliver, slubbing, roving or like staple fiber product by feeding forward the bundle, separating the filaments of the bundle from each other at the end of the bundle, cutting from such separated filaments a predetermined length to yield a group of fibers, and repeating these operations so as to obtain a succession of groups of separated fibers, and, while the cut fibers are still separate assembling the groups of fibers in such a manner that the forward ends of fibers of each group extend beyond, i. e., overlap, the rearward ends of fibers of the preceding group to such an extent that upon subsequently compacting the fibers a coherent continuous product consisting of staple fiber may be produced, then compacting the fibers into the continuous staple fiber product, and drafting such product into a finer product.

The invention enables a sliver or like staple fiber product to be formed under optimum conditions as regards output, size of delivery and take-up package, and so on, the sliver or like product then being capable of conversion to any desired finer product by suitable adjustment of the degree of drafting to which it is subjected.

The sliver, slubbing, roving or like product may be wound on a package as, for example, by a flyer device, or may be collected in a sliver can or like container, concomitantly with the manufacture of the product. The sliver can may be caused to rotate in order to insert a small amount of twist in the product. Any twist, however, whether inserted in the product by a flyer winding device or by a rotatable sliver can is insufficient to hinder the subsequent drafting of the product.

By reason of the separated condition of the fibers of the group cut from the continuous filaments and the arranging of the groups so that the forward ends of fibers of each group extend beyond or overlap the rearward ends of fibers of the preceding group, the fibers of the successive groups intermingle, to enable the groups to be compacted into a coherent product.

The separation of the filaments over the re-

quisite length (i. e., a length longer than the length of staple desired) may be effected as the filaments are about to be cut into the groups of fibers. Thus, the end of the bundle may be subjected to the action of a gaseous blast that serves to separate the component filaments of the bundle from each other and, at the same time, feed them to a cutting device.

In order to control the separated filaments during cutting, means may be provided to seize and hold the free ends of the filaments as, for example, an endless permeable support, in the form of a permeable band or a drum or wheel having a permeable surface, through which suction is applied. With such an arrangement the free ends of the filaments are drawn to and held on the permeable surface by the suction and while so held are cut by the cutting means. By moving the surface at a predetermined rate away from the cutting device in the direction of the length of the fiber groups, each group may be arranged to overlap the preceding group to the required extent.

The regularity of the cross-section of the continuous staple fiber sliver, slubbing, roving or like product may be enhanced by ensuring that the fibers produced by cutting the separated filaments are so disposed that the ends of the fibers are distributed along the length of the product. Thus, groups of separated fibers may be cut from two or more bundles of continuous filaments and associated and compacted into a single continuous staple fiber product of the desired denier, or groups of separated filaments derived from one or more bundles may be cut so that the ends of the fibers formed from each group are staggered with respect to the ends of the fibers formed from the other groups, the groups of fibers so formed then being associated and compacted into a single continuous staple fiber product having fiber ends distributed at regular intervals along its length. Again, the separated filaments of a bundle may be cut obliquely to their length so that the ends of the fibers of each group are progressively staggered lengthwise of the group, the ends maintaining such staggered disposition (whether or not the groups are associated with other groups cut from another bundle or other bundles) and forming a continuous sliver, slubbing, roving or like product of regularly distributed fibers.

A form of cutting device suitable for dealing with the separated filaments, especially where the filaments are spread into a flat band or bands, comprises a pair of multi-toothed cutting mem-

bers (e. g., as used in a hair-clipper) of a width sufficient to accommodate the separated filaments. The cutting device is preferably disposed out of the path of the separated filaments, the 5 filaments and the cutting device being brought intermittently into engagement with each other, e. g., by deflecting the filaments into the teeth of the cutting device.

The continuous fibrous product formed in the 10 manner previously outlined above may be drafted and spun into yarn continuously with the compacting of the fiber groups. Thus a ring, cap, or flyer spinning device furnished with drafting rollers may be arranged so as to draft the compacted product and twist and wind it on to a bobbin, spool, or cop, the package of yarn thus produced being formed into fabric either in the single state or after doubling with yarn of the same or different construction.

20 When forming a continuous staple fiber sliver, slubbing, roving or like product from continuous filaments of material such as cellulose acetate or other organic derivative of cellulose having a high di-electric strength and consequently liable to retain charges of static electricity, it is found that by rubbing the filaments prior to separating them a charge of static electricity is induced in the filaments, the charge causing the filaments to repel each other with the result that the filaments are given a desirable preliminary spreading prior to being separated. Such preliminary spreading may be enhanced by limiting the opportunity for the static charge to leave the filaments prior to being separated, as by covering 25 with rubber or like electrical insulating material machine parts with which the electrified filaments are likely to contact.

By way of example the invention will now be described in greater detail with reference to the accompanying diagrammatic drawing, of which—

40 Fig. 1 is a part cross-sectional end elevation of a filament-converting machine generally similar to that shown in U. S. application S. No. 155,226, filed July 23, 1937, corresponding to British application No. 21210/36;

45 Fig. 2 is a diagram illustrating the construction of the continuous product formed in the apparatus shown in Fig. 1;

Fig. 3 is a part cross-sectional end elevation of 50 a drawing and spinning device, and

Fig. 4 is a detail of Fig. 1 on a larger scale.

In the following description reference is made only to the salient features of the apparatus of Fig. 1, a more detailed description of which may be had from U. S. application 155,226, filed July 23, 1937, corresponding to British application No. 21210/36.

Referring to Fig. 1 a thick bundle, or band or 60 thread of substantially twistless continuous filaments 8 having a total denier of the order of the denier of a sliver, slubbing, roving or like product is withdrawn from a supply bobbin 9 by a pair of nip rollers 10, the filaments passing from the supply bobbin to the rollers by way of guides 11 and through a "gate" tension device 12. The nip rollers 10 feed the filaments to an ejector nozzle 13 formed with a flat flared ejecting orifice 14, the nozzle being fed with compressed air from a supply pipe 15.

70 The expression "substantially twistless" as used in connection with the bundle, band or thread is intended to mean that the bundle or the like contains no twist, or that if any twist is present in the bundle it should be insufficient to

hinder free separation one from the other of the component filaments at the end of the bundle.

The air blast issuing from the ejecting orifice 14 ejects from the orifice a length of the continuous filaments longer than the length of the staple desired and separates the ejected filaments one from the other in the form of a substantially flat band during the ejection. The band-wise spreading of the filaments facilitates their subsequent manipulation, as will appear hereinafter. The bundle of filaments should not contain a finish that prevents the air current from separating the filaments, and for this reason it is desirable to employ unlubricated filaments.

On being ejected from the orifice 14 the separated filaments 8 extend across an endless permeable band 16 which is driven over the surface of a suction conduit 17 by a roller 18 engaging the inside of the band. The band is kept taut by an idler roller 19 which is spring-urged into contact with the band. The suction conduit 17 is connected to a suction vessel 20 by a pipe 21.

As shown clearly in Figs. 1 and 4 the conduit 17 is of flattened cross-section and is perforated at 2 points 22, 23, two separate streams of air thus flowing into the conduit through the permeable band 16 as indicated by the arrows. On the ejection of the filaments 8 from the orifice 14 the ends of the filaments are attracted to and held on the band 16 by the suction due to the 30 perforations 22.

Substantially simultaneously with the sucking to the band 16 of the filament ends a cam 40, of a series of cams 40, 41, 42 and 43, fixed to a driving shaft 44 (see Fig. 4) is caused by the rotation of the shaft to press the stem 45 of a valve 46 controlling the supply of air to the nozzle 13. The pressing of the stem interrupts the supply of air to the nozzle, and the separated filaments are left extending from the orifice 14 to the 40 band 16.

The succeeding cam 41 (partly hidden from view by the cam 40) now bears against the end 47 of a deflecting lever 48, and causes the lever to rock about its pivot 49. The lever 48 is formed with a forked portion 24 which is caused by the rocking of the lever to bear downwardly upon the separated filaments 8 extending from the orifice 14 to the band 16, and deflect the filaments into the teeth of a multi-toothed cutting device 25 which is disposed obliquely with respect to the width of the separated filaments. On deflection, one limb of the forked portion 24 lies to each side of the cutting device 25 to ensure proper engagement of the filaments with the 55 teeth.

On engagement of the filaments 8 by the teeth of the cutting device 25, the next cam, 42, bears against the end 50 of a lever 51 and causes the lever to rock about its pivot 52. The lever is 60 connected by an upright arm 53 to the cutting device 25, the rocking of the lever thus operating the device to cut the filaments. Two or more cutting devices 25 may be arranged for operation by common actuating means, and two or more deflecting levers 48 may likewise be arranged for common actuation.

The freshly cut end of the fiber-group thus formed is sucked away from the cutting device 25 and on to the band 16 by the air current flowing 70 into the conduit through the perforations 23, the air current being in part concentrated on the teeth of the cutting device by a shield 26 arranged between the cutting device and the perforations 23. A staple length or group of cut 75

fibers is thus formed and laid on the surface of the moving band 16.

On operation of the cutting device 25 a pivoted guiding member 27 normally disposed behind the continuous filaments 8 as they proceed in a straight line from the nip rollers 10 to the nozzle 13 is moved forwardly (viz. to the right as shown in Fig. 1) by the cam 43, and in so moving deflects the filaments from the straight line and 10 draws their cut ends backwardly towards the orifice 14 clear of the teeth of the cutting device 25 to free the filaments for further forward movement.

With the filaments drawn clear of the cutting device, the guide 27 is retracted to its normal inoperative position and the air blast is restarted to separate and eject the filaments over the band 16 again from the orifice 14, by the continued rotation of cams 43 and 48. The ends of the 20 filaments are again sucked to the band 16 in the manner shown in Fig. 1 and the sequence of operations described above is repeated.

The separation of the continuous filaments in such a way as to feed them to the cutting device 25 as a flat band or bands enables the cut ends of the fibers to maintain their separated relation during and after cutting, an arrangement which is particularly advantageous when the cutting is effected obliquely to the length of the continuous 30 filaments. With fiber groups arranged in the form of a flat band, moreover, the intermingling of fibers at the ends of the groups with end fibers of other groups, and the compacting of the groups into the continuous product, as described below, 35 are facilitated.

The rate of progress of the filaments 8 from the orifice 14 is dependent on the rate of rotation of the nip rollers 10 and by adjusting such rotation the staple length of the groups laid on the band 16 can be regulated. On being cut, each fiber-group is sucked flat to the band, the suction continuing to operate through the thickness of the group of fibers to attract the ends of the filaments to the band again in readiness for the cutting of 40 a further group of fibers. In this manner each group can be made to overlap the preceding group to any desired extent, as shown diagrammatically in Fig. 2. Similarly, the degree of overlap of the cut groups may be regulated by varying the 45 rate of movement of the band 16, quicker movement producing less overlap and vice versa. With the filaments delivered at a constant rate to a cutting device working with a constant frequency the groups are substantially uniform in length.

While the nip rollers 10 feed the continuous filaments 8 to the nozzle 13 continuously, and the filaments are ejected from the nozzle to the band intermittently, the ejecting and cutting operations are effected in such rapid succession that any small amount of slack formed in the filaments between the rollers and the nozzle due to the continued feed of the filaments during the periods in which the compressed air supply is stopped, is insignificant and is quickly taken up 55 by the air blast when the air supply is restarted. The nip rollers 10 may, however, be driven intermittently in accordance with the timing of the air blasts.

In the manner described above a continuous 70 line or assembly of overlapping groups of fibers (indicated at 28 in Fig. 2) is formed on the band 16.

The band feeds the assembly 28 forwardly to a pair of endless traveling rubbing bands 29 driven by rollers 30. The upper rubbing band of the 75

pair is reciprocated transversely with respect to the assembly 28 in order to roll and compact it into a coherent substantially cylindrical product 31 which is wound on a bobbin 32 by a flyer device 33. The flyer device inserts a small amount 5 of twist in the product 31, the twist, however, being insufficient to hinder or prevent subsequent drafting of the product. If desired, the product may be collected in a sliver can or like container which may be rotated to insert a small amount of 10 twist in the product, the degree of twist, again, being insufficient to hinder or prevent subsequent drafting of the product.

Filaments or fibers of different materials and/or characteristics may be incorporated in 15 the continuous staple fiber product in order to produce fancy effects (e. g., cross-dyed effects) in yarn formed from the product and in fabrics containing such yarn. By incorporating in the product materials capable of bringing about a change 20 in its cross-section, a product having slub effects may be obtained. Different continuous filaments may be incorporated in the product; for example, cellulose acetate and viscose filaments may be simultaneously separated and cut into fiber 25 groups which are compacted and formed into a single product.

On filling of the bobbin 32, the bobbin is removed and taken to the spinning machine illustrated in Fig. 3, where the product 31 is unwound and passed, by way of a guide 34, between pairs of drawing rollers 35, 36. The rollers 36 rotate at a higher peripheral speed than the rollers 35 so as to reduce the product to one of 30 finer denier, the reduced product being fed to a ring spinning device 37 which twists the product 35 into yarn 38 and winds it on a cop 39.

As shown in Figs. 1 and 4, the cutting device 25 is disposed obliquely with respect to the width of the separated filaments so that the ends of the 40 component fibers of each group are progressively staggered lengthwise of the group. Such arrangement brings about an even distribution of the ends of the filaments along the length of the assembly 28 (and hence along the length of the 45 ultimate yarn 38), the arrangement assisting in the production of a product having substantially uniform strength throughout its length.

It will be apparent from the foregoing description that since the cut groups of fibers are caused 50 to overlap, the denier of the resultant fibrous product 31 is greater than that of the initial bundle of continuous filaments 8, the increase in denier depending on the degree to which the fibers overlap, more overlap giving a product of greater 55 denier, and vice versa.

While apparatus for the treatment of one bundle of filaments 8 only has been referred to in the foregoing description, it will be understood that a number of such forms of apparatus could 60 be disposed in side-by-side relation in order simultaneously to treat any desired number of continuous filament bundles. Also, where for any reason it is desired to produce a sliver, slubbing, roving or like product having a denier sensibly 65 greater than that of the initial bundle of continuous filaments 8, any suitable number of separate bundles of filaments may be associated and fed to the nip rollers 10 to be formed into a single product.

When cutting and converting continuous filaments of material such as cellulose acetate or other organic derivative of cellulose having a high dielectric strength and consequently liable to retain charges of static electricity, it is found 70 75

that the rubbing of the continuous filaments by the "gate" tension device 12 in addition to subjecting the filaments to the desired tension electrifies the filaments and thus causes them to repel each other with the result that the filaments are given a desirable preliminary spreading prior to entering the ejector nozzle 13. Such preliminary spreading may be maintained by limiting the opportunity for the static charge to leave the filaments prior to their entering the nozzle, and for this reason at least the upper nip roller 10 may with advantage be covered with rubber or other electrical insulating material.

In order to prevent excessive wear on any one portion of the nip rollers 10 the filaments 8 may be traversed to and fro along the length of the rollers.

Having described our invention, what we desire to secure by Letters Patent is:

- 20 1. Process for the manufacture of a staple fiber product, which consists in continuously converting a substantially twistless bundle of associated continuous filaments into a staple fiber product by feeding forward the bundle, separating the filaments of the bundle from each other at the end of the bundle so that the filaments assume a fan shape, cutting from such fan-shaped separated filaments a predetermined length to yield a group of fibers and repeating these operations so as to obtain a succession of groups of separated fibers, and, while the cut fibers are still separate, assembling the groups of fibers in such a manner that the forward ends of fibers of each group overlap the rearward ends of fibers of the preceding group to such an extent that upon subsequently compacting the fibers a coherent continuous sliver, slubbing, roving or like staple fiber product may be produced, then compacting the fibers into the continuous staple fiber product, and drafting such product into a finer product.
- 40 2. Process for the manufacture of a staple fiber product, which consists in continuously converting a substantially twistless bundle of associated continuous filaments into a staple fiber product by feeding forward the bundle, subjecting the end of the bundle to the action of a gaseous blast so as to separate the filaments of the bundle from each other for a length longer than the length of staple desired, cutting from such separated filaments a predetermined length to yield a group of fibers and repeating these operations so as to obtain a succession of groups of separated fibers, and, while the cut fibers are still separate, assembling the groups of fibers in such a manner that the forward ends of fibers of each group overlap the rearward ends of fibers of the preceding group to such an extent that upon subsequently compacting the fibers a coherent continuous sliver, slubbing, roving or like staple fiber product may be produced, then compacting the fibers into the continuous staple fiber product, and drafting such product into a finer product.
- 60 3. Process for the manufacture of a staple fiber product, which consists in continuously converting a substantially twistless bundle of associated continuous filaments into a staple fiber product by feeding forward the bundle, separating the filaments of the bundle from each other at the end of the bundle for a length longer than the length of staple desired and so that the filaments assume a fan shape, seizing the free ends of the fan-shaped group of filaments, cutting from the seized filaments a predetermined length to yield a group of fibers and repeating these operations so as to obtain a succession of groups of

separated fibers, and, while the cut fibers are still separate, assembling the groups of fibers in such a manner that the forward ends of fibers of each group overlap the rearward ends of fibers of the preceding group to such an extent that upon subsequently compacting the fibers a coherent continuous sliver, slubbing, roving or like staple fiber product may be produced, then compacting the fibers into the continuous staple fiber product, and drafting such product into a finer product.

4. Process for the manufacture of a staple fiber product, which consists in continuously converting a substantially twistless bundle of associated continuous filaments into a staple fiber product by feeding forward the bundle, subjecting the end of the bundle to the action of a gaseous blast so as to separate the filaments of the bundle from each other for a length longer than the length of staple desired, seizing the free ends of the filaments, cutting from the seized filaments a predetermined length to yield a group of fibers and repeating these operations so as to obtain a succession of groups of separated fibers, and, while the cut fibers are still separate, assembling the groups of fibers in such a manner that the forward ends of fibers of each group overlap the rearward ends of fibers of the preceding group to such an extent that upon subsequently compacting the fibers a coherent continuous sliver, slubbing, roving or like staple fiber product may be produced, then compacting the fibers into the continuous staple fiber product, and drafting such product into a finer product.

5. Process for the manufacture of a staple fiber product, which consists in continuously converting a substantially twistless bundle of associated continuous filaments into a staple fiber product by feeding forward the bundle, separating the filaments of the bundle from each other at the end of the bundle for a length longer than the length of staple desired, applying suction to the free ends of the separated filaments to seize them, cutting from the seized filaments a predetermined length to yield a group of fibers and repeating these operations so as to obtain a succession of groups of separated fibers, and, while the cut fibers are still separate, assembling the groups of fibers in such a manner that the forward ends of fibers of each group overlap the rearward ends of fibers of the preceding group to such an extent that upon subsequently compacting the fibers a coherent continuous sliver, slubbing, roving or like staple fiber product may be produced, then compacting the fibers into the continuous staple fiber product, and drafting such product into a finer product.

6. Process for the manufacture of a staple fiber product, which consists in continuously converting a substantially twistless bundle of associated continuous filaments into a staple fiber product by feeding forward the bundle, separating the filaments of the bundle from each other at the end of the bundle for a length longer than the length of staple desired, extending the separated filaments over a permeable support, passing a gaseous current through the support so as to seize the free ends of the filaments and hold them to the support, cutting from the seized filaments a predetermined length to yield a group of fibers and repeating these operations so as to obtain a succession of groups of separated fibers, and, while the cut fibers are still separate, assembling the groups of fibers in such a manner that the forward ends of fibers of each group overlap

the rearward ends of fibers of the preceding group to such an extent that upon subsequently compacting the fibers a coherent continuous sliver, slubbing, roving or like staple fiber product 5 may be produced, then compacting the fibers into the continuous staple fiber product, and drafting such product into a finer product.

7. Process for the manufacture of a staple fiber product, which consists in continuously converting a plurality of substantially twistless bundles of associated continuous filaments into a staple fiber product by feeding forward the bundles, separating the filaments of each bundle from each other at the end of the bundle for a 10 length longer than the length of staple desired and so that the filaments assume a fan shape, cutting from the end of each fan-shaped bundle a predetermined length of the separated filaments so as to yield a group of fibers from each 15 bundle, and repeating these operations to obtain from each bundle a succession of groups of separated fibers, and, while the cut fibers are still separate, associating the successions of groups of fibers in such a manner that the forward ends 20 of the fibers of each group overlap the rearward ends of the fibers of the preceding group and compacting the associated groups into a single continuous sliver, slubbing, roving or like staple fiber product, and drafting such product into a 25 finer product.

8. Process for the manufacture of a staple fiber product, which consists in continuously converting a substantially twistless bundle of associated continuous filaments into a staple fiber product by feeding forward the bundle, separating the filaments at the end of the bundle into the form of a flat fan-shaped band for a length longer than the length of staple desired, cutting from such fan-shaped separated filaments a predetermined length to yield a group of fibers and repeating these operations so as to obtain a succession of groups of separated fibers, and, while the cut fibers are still separate, assembling the groups of fibers in such a manner that the forward ends of fibers of each group overlap the rearward ends of fibers of the preceding group to such an extent that upon subsequently compacting the fibers a coherent continuous sliver, slubbing, roving or like staple fiber product may be 45 produced, then compacting the fibers into the continuous staple fiber product, and drafting such product into a finer product.

9. Process for the manufacture of a staple fiber product, which consists in continuously converting a substantially twistless bundle of associated continuous filaments into a staple fiber product by feeding forward the bundle, separating the filaments of the bundle from each other 50 at the end of the bundle for a length longer than the length of staple desired and so that the filaments assume a fan shape, cutting such fan-shaped separated filaments obliquely across the width of the bundle to yield a group of separated, 55 staggered fibers of predetermined length, and repeating these operations so as to obtain a succession of such groups of fibers, and, while the cut fibers are still separate, assembling the groups of fibers in such a manner that the forward ends 60 of fibers of each group overlap the rearward ends of fibers of the preceding group to such an extent that upon subsequently compacting the fibers a coherent continuous sliver, slubbing, roving or like staple fiber product may be produced, then compacting the fibers into the continuous staple fiber product, and drafting 65 such product into a finer product.

75

fiber product, and drafting such product into a finer product.

10. Process for the manufacture of a staple fiber product, which consists in continuously converting a substantially twistless bundle of associated continuous filaments into a staple fiber product by feeding forward the bundle, separating the filaments of the bundle from each other at the end of the bundle for a length longer than the length of staple desired and so that the filaments assume a fan shape, cutting from such fan-shaped separated filaments a predetermined length to yield a group of fibers and repeating these operations so as to obtain a succession of groups of separated fibers, and, while the cut fibers are still separate, assembling the groups of fibers in such a manner that the forward ends of fibers of each group overlap the rearward ends of fibers of the preceding group to such an extent that upon subsequently compacting the fibers a 20 coherent continuous sliver, slubbing, roving or like staple fiber product may be produced, then rubbing the assembled groups of fibers so as to roll and compact them into the continuous staple fiber product, and drafting such product into 25 a finer product.

11. Process for the manufacture of a staple fiber product, which consists in continuously converting a substantially twistless bundle of associated continuous filaments into a staple fiber product by feeding forward the bundle, separating the filaments of the bundle from each other at the end of the bundle for a length longer than the length of staple desired and so that the filaments assume a fan shape, cutting from such fan-shaped separated filaments a predetermined length to yield a group of fibers and repeating these operations so as to obtain a succession of groups of separated fibers, and, while the cut fibers are still separate, assembling the groups of fibers in such a manner that the forward ends of fibers of each group overlap the rearward ends of fibers of the preceding group to such an extent that upon subsequently compacting the fibers a 30 coherent continuous sliver, slubbing, roving or like staple fiber product may be produced, then compacting the fibers into the continuous staple fiber product, drafting such product into a finer product. 35

12. Process for the manufacture of a staple fiber product, which consists in continuously converting a substantially twistless bundle of associated continuous filaments of artificial material into a staple fiber product by feeding forward the bundle, separating the filaments of the bundles 40 from each other at the end of the bundle so that the filaments assume a fan shape, cutting from such fan-shaped separated filaments a predetermined length to yield a group of fibers and repeating these operations so as to obtain a succession of groups of separated fibers, and, while the cut fibers are still separate, assembling the groups of fibers in such a manner that the forward ends of fibers of each group overlap the rearward ends of fibers of the preceding group to 45 such an extent that upon subsequently compacting the fibers a coherent continuous sliver, slubbing, roving or like staple fiber product may be produced, then compacting the fibers into the continuous staple fiber product, drafting such product into a finer product. 50

13. Process for the manufacture of a staple fiber product, which consists in continuously converting a substantially twistless bundle of associated continuous filaments of cellulose acetate 55

into a staple fiber product by feeding forward the bundle, separating the filaments of the bundle from each other at the end of the bundle so that the filaments assume a fan shape, cutting 5 from such fan-shaped separated filaments a predetermined length to yield a group of fibers and repeating these operations so as to obtain a succession of groups of separated fibers, and, while the cut fibers are still separate, assembling the 10 groups of fibers in such a manner that the forward ends of fibers of each group overlap the rearward ends of fibers of the preceding group to such an extent that upon subsequently compacting the fibers a coherent continuous sliver, slubbing, 15 roving or like staple fiber product may be produced, then compacting the fibers into the continuous staple fiber product, and drafting such product into a finer product.

14. Process for the manufacture of a staple fiber product, which consists in continuously converting a substantially twistless bundle of associated continuous filaments of cellulose acetate into a staple fiber product by feeding forward the bundle, separating the filaments of the bundle from each other at the end of the bundle for a length longer than the length of staple desired and so that the filaments assume a fan shape, cutting from such fan-shaped separated filaments a predetermined length to yield a group of fibers and repeating these operations so as to obtain a succession of groups of separated fibers, and, while the cut fibers are still separate, assembling the groups of fibers in such a manner that the forward ends of fibers of each group 30 overlap the rearward ends of fibers of the preceding group to such an extent that upon subsequently compacting the fibers a coherent continuous sliver, slubbing, roving or like staple fiber product may be produced, then compacting the fibers into the continuous staple fiber product, and drafting such product into a finer product.

15. Process for the manufacture of a staple fiber product, which consists in continuously converting a substantially twistless bundle of associated continuous filaments of cellulose acetate into a staple fiber product by feeding forward the bundle, electrifying the bundle to cause mutual repulsion and spreading of the filaments, separating the spreading filaments of the bundle from each other at the end of the bundle for a length longer than the length of staple desired, cutting from such separated filaments a predetermined length to yield a group of fibers and repeating

these operations so as to obtain a succession of groups of separated fibers, and, while the cut fibers are still separate, assembling the groups of fibers in such a manner that the forward ends of fibers of each group overlap the rearward ends 5 of fibers of the preceding group to such an extent that upon subsequently compacting the fibers a coherent continuous sliver, slubbing, roving or like staple fiber product may be produced, then compacting the fibers into the continuous 10 staple fiber product, and drafting such product into a finer product.

16. Process for the manufacture of a staple fiber product, which consists in continuously converting a substantially twistless bundle of associated continuous filaments into a staple fiber product by feeding forward the bundle, separating the filaments at the end of the bundle into the form of a flat fan-shaped band, cutting from such fan-shaped separated filaments a predetermined length to yield a group of fibers and repeating these operations so as to obtain a succession of groups of separated fibers, and, while the cut fibers are still separate, assembling the groups of fibers in such a manner that the forward ends of fibers of each group overlap the rearward ends of fibers of the preceding group to such an extent that upon subsequently compacting the fibers a coherent continuous sliver, slubbing, roving or like staple fiber product may 20 be produced, then compacting the fibers into the continuous staple fiber product, and drafting such product into a finer product.

17. Apparatus for the manufacture of a staple fiber product, comprising means for feeding forward a bundle of continuous filaments, means for separating the filaments of the bundle from each other at the end of the bundle in such a manner that they assume a fan shape, a cutting device adapted to cut from the fan-shaped separated 35 filaments a succession of groups of separated fibers of predetermined length, means for assembling the groups of fibers in such a manner that the forward ends of fibers of each group overlap the rearward ends of fibers of the preceding group 40 to such an extent that upon subsequently compacting the fibers a coherent continuous sliver, slubbing, roving or like staple fiber product may be produced, means for compacting the fibers into a continuous staple fiber product, and means 45 for drafting such product into a finer product.
